TIME RECORDING DEVICE

Elbert V. Abbott, San Francisco, Calif., assignor
to Electric Time Recording Register Company,
San Francisco, Calif., a copartnership consist-
ing of Thomas Harris and Elbert V. Abbott

Application May 22, 1944, Serial No. 536,730

2 Claims. (Cl. 234—53.5)

1

This invention relates to time recording apparatus in general, and more specifically to means in such apparatus for detecting fraud or tampering with time identified records.

The provision of apparatus for printing the year, month and exact time on a sheet dispensed from a register or recorder is old. Such apparatus ordinarily employs wheels bearing type carrying the desired data, and one or more of such wheels may be clock driven so as to always present a type designating the correct time to within a fraction of a minute to a platen and the sheet for printing such time on the sheet when the latter is dispensed from the apparatus. It is old to use a sheet in the form of a roll of tickets or in the form of a strip to be torn off or in other dispensable forms. Where rolls are used there may be several of such rolls with duplicating ribbons or carbon paper or both so arranged as to duplicate the data written on the top sheet or printed thereon by the printing apparatus, and ordinarily one of such sheets is retained within a cabinet that encloses the time recording apparatus. Such cabinet is locked so as to prevent manipulation of the time recording or driving mechanism. As it is old to electrically drive certain parts of the recording mechanism, as through a motor similar to that used in electrically driven clocks, a plug and cord is usually provided for connecting the electrical circuit within the cabinet with the main source of supply of electricity.

Heretofore irrespective of adopting reasonable precautions against tampering, the doors of cabinets enclosing time recording mechanisms have been unlocked by unauthorized use of keys made therefor or by forged copies of the true keys. Tampering with the time recording mechanism has resulted whereby fraud has been perpetrated and has been undetected, or if detected the perpetrator has been undetected. In other instances discoveries of incorrect time printings on sheets or tickets have been blamed by operators on the mechanism and in the absence of reasonable proof of actual tampering, such explanation in many instances must be accepted although the explanation is untrue.

Other known methods of altering records where an electrically driven element, such as a motor for driving the time recording type is used, has been to disconnect the source of supply from the locked cabinet that encloses the motor and printer, and after an interval has elapsed, to reconnect the source.

One of the objects of this invention is the pro-

2

vision of simple and effective means for detecting whether or not the cabinet door has been opened and the approximate time of such opening.

5 Another object of the invention is the provision of simple and effective means for detecting whether or not the source of electrical power to the time recording mechanism has been disconnected, and the time such disconnection occurred.

10 A still further object of the invention is the provision of means in an electrically actuated time recorder of the character above mentioned for detecting whether or not the door to the cabinet enclosing the recorder has been opened and whether or not the source of supply to said recorder has been disconnected, and the time when either of such operations occurred, which detection is in the form of different symbols adapted 15 to be automatically printed on the record sheet simultaneously with printing of the time thereon.

20 Other objects and advantages will appear in the description and drawings.

The illustrations and description thereof that 25 follows are not intended to be restrictive of the invention, but merely illustrative of a form thereof. The invention is solely concerned with detecting such unauthorized occurrences as the opening of the door of the cabinet and disconnection 30 of the source of electrical supply and which operations have occurred in a manner that would remain undetected were it not for my invention.

In the drawings,

35 Fig. 1 is a perspective view of a cabinet. Fig. 2 is a plan view of one form the printed record may take, the same being in the form of a sheet in a strip that is adapted to be dispensed from a roll or from a manifoldeled pad or stack.

40 Fig. 3 is a perspective view of part of a cabinet showing in dotted line an actuator means on the door instead of being on the lock or part of the lock.

45 Fig. 4 is a diagrammatic or schematic view of an electrical circuit that may be employed and the various elements in such circuit.

In detail, the cabinet 1 (Fig. 1) is provided with an opening 2 in its upper side for withdrawal of portion 3 of a record sheet 4 from within the cabinet. Any convenient support may be provided for said portion 3 for writing thereon, such support being old in registers and time recorders. Several of such sheets may be withdrawn from the cabinet with carbon paper or the like between 50 them for duplicating data written on the top

55

sheet, and it is conventional to have one of such sheets automatically fed back into the cabinet without being exposed.

A cord 5 having a connector plug 6 at one end is provided for connecting the circuit within the cabinet with a source of electrical power. A push button 7 is also provided for causing actuation of the time recording apparatus and usual drive means (not shown) for dispensing one or more of the record sheets.

Cabinet 1 (Fig. 1) is provided with an opening closed by a door 8 hinged thereto along one edge of the latter for swinging to a position uncovering the opening. This opening provides for authorized access to the duplicate record sheet within the cabinet as well as to the time recording mechanism and circuit so that adjustments and repairs may be effected. A lock 9 is provided for locking the door against unauthorized opening thereof, which lock may be of the type having a revolvable latch element 10 that effects the locking.

Before describing the electrical circuit itself, it will clarify the description to enumerate certain of the elements that may be employed in such circuit.

In Fig. 4 the time printer is indicated at the top of the view as comprising a row of wheels 11 that respectively carry type for printing the desired data. The actual hour and minute type, at least, may be driven by electric motor 12, which motor may be the type used in electric clocks. In Fig. 2 at the upper edge of the strip 4, a typical imprint is indicated at 13, which imprint shows that it was made on May 22 at 4:16 p. m. At this point it should be stated that the strip or sheet 4 may have its separate portions or sections serially numbered as at 14, which numbering is ordinarily done before the sheet or strip is put into the cabinet. The dot-dash line 15 in Fig. 4 connecting clock 12 with the time printing wheel or wheels may represent any suitable driving connection, the same being conventional.

A plurality of sheets 5 over wheels 11 (Fig. 4) may constitute the original and carbon copy sheets or strips, and over these and longitudinally of the row of type wheels is a platen 17 that is adapted to be forced against said sheets and the type on the wheels 11 by means of a rocker arm 18 that may pivotally carry said platen, as indicated, or that may merely be forced at one end against said platen to cause printing of the imprint 13 (of Fig. 2) or whatever characters are represented by the type.

The rocker arm 18 is pivotally supported on pivot 19 on any suitable portion of a stationary frame member 20 of the time recorder. The end of said arm 18 that is at the opposite side of pivot 20 from platen 17 is positioned over an extension 21 of core 22 of a solenoid generally designated 23. Upon energizing the coil 24 of solenoid 23 the extension 21 will strike the end of arm 18 that is above the same thereby causing the platen to be forced toward the time printer that comprises wheels 11.

At the opposite ends of the row of wheels 11, or in any other position to be operable for printing by the actuation of plate 17, is a pair of printing type 25, 26 carried on the upper ends of extensions 27, 28 of solenoid cores 29, 30 of solenoids that are respectively designated 31, 32. The type 25 may be called the door printer inasmuch as type 25 will print after an opening of the door at the same time as the time printer is actuated

while type 26, which will be called the circuit printer, will print after a disconnection and reconnection of the source of electrical power to the circuit inside cabinet 1, as would happen were plug 6 to be disconnected and then reconnected. The printing by the circuit printer or door printer is also simultaneously done with a printing by the time printer. This is the reason for positioning the type 25, 26 below the platen 17.

In Fig. 4 the type 25, 26 are not elevated sufficiently to result in printing by actuation of the platen 17, but upon energizing the coil 33 of solenoid 31 or upon energizing the coil 34 of solenoid 32, the door printer or circuit printer will be elevated as indicated in dotted line positions 35, 36 for printing by actuation of platen 17 upon energizing solenoid 23. Of course both the door printer and circuit printer may print at the same time.

In Fig. 2 the character "O" indicated at 37 may represent a printing by the door printer, showing that the door has been opened, or the character "X" as indicated at 38 may show that the source of power has been disconnected.

The latch 10 of lock 9, as will later be described more in detail, functions to "set" or to move the door printer into operating position, while a relay 56 energized by plug 6 being inserted in its socket for connecting the cord 5 or source of power with the circuit in cabinet 1 functions to position the circuit printer for printing, as will later be described.

Means for driving a conventional mechanism (not shown) for issuing each ticket upon pressing the button 7, is a motor 39, said motor also driving cams 40, 41 for performing necessary functions in the carrying out of the desired results.

In the arrangement of parts as seen in Fig. 4, the plug 6 connects the two main circuit wires 45, 46 with the main source of electrical power, such as electrical conduit 5, and the circuit printer 26 has already made a printing on one of the tickets 45 or sheets 3, and has dropped back to inoperative position in which it will remain until the source of power is again disconnected and reconnected with the circuit.

Upon inserting plug 6 in its socket so as to connect the circuits 45, 46 with the source of power, the said circuit will be closed through wires 46 to 50 inclusive, coil 34 of solenoid 32, wire 54, normally closed switch 55 (dotted line position) of relay 56, and wires 57, 58, whereby solenoid 32 is energized and the circuit printer will be elevated for printing upon actuation of platen 17.

The extension 28 of the core of solenoid 32 may carry a switch 59, which switch will close contacts 60, 61 at the ends of wires 62, 63 when said switch is carried to dotted position 64 by reason of energizing of said solenoid.

The wire 62 connects with wire 46 through wires 47 to 49 inclusive, while wire 63 connects with one end of coil 24 of solenoid 23. The opposite end of said solenoid coil is connected with wire 45 completing the circuit, whereby said solenoid will be energized for causing actuation of platen 17. The time printer and circuit printer will accordingly print the symbols 13 and 38 of Fig. 2.

Upon upward movement of the extension 21 of solenoid 23, a switch 65 breaks normally closed contacts 66 and closes contacts 67. One side of contact 67 connects through wire 68 with wire 45 that leads to plug 6, while the other side of the

contact 67 connects with one end of wire 69 that connects with wire 46 by way of normally closed relay armature (dotted position) 70 of relay 58 and wire 71, then through the coil of relay 56 to wires 72, 49, 48, 47, thereby energizing relay 56 so as to break the circuit to solenoid 32 when the solenoid 32 is de-energized and its core will drop. Upon so energizing relay 56, normally closed switch 55 will move to connect the relay coil in the circuit through wires 151, 152 to hold the switch in full line position. Switch 59 of solenoid 32 at the same time will break the connection between contacts 60, 61, thereby de-energizing solenoid 23.

The de-energizing of solenoid 23 will result in its core dropping so that its lower end will strike one end 73 of a rocker arm 73 causing the opposite end 75 of said arm to strike one end of a generally centrally pivoted latch 76 for disengaging the opposite end of said latch from holding cam 40 that is driven by motor 39. The swinging of latch 76 away from cam 40 closes switch 77 which closing results in starting motor 39 through wires 78, 79 that connect one of the motor terminals with wire 47 through wires 43, 49, 50. Wire 80 connects the other terminal with wire 45.

As stated, motor 39 will drive cam 40 one revolution and stop, and the same revolution will drive any suitable rollers (not shown) for issuing one of the sheets 4.

Any suitable means, such as a spring 31 may restore arm 73 to a position in which the latch 76 holds the cam 40 after one revolution thereof has been completed, and switch 77 will, of course, be automatically opened as soon as the cam 40 has about completed one revolution, thereby stopping motor 39. Upon the dropping of core 22 the switch 65 will connect wires 63 and 83 extending to wires 84, 85 that respectively connect with one of the coil terminals of a pair of relay switches 86, 87.

The motor 39 also revolves cam 41 at the same time that it revolves cam 40. Revolving of cam 41 closes switch 88, thereby energizing relay coil 87 through a wire 89 that connects with the other coil terminal of said relay through wire 85. Thus the circuit through the relay coil is completed, since one of the contacts of switch 88 connects with wire 46 while the other contact of said switch closes the circuit to wire 45 through the relay coil by way of wires 89, 85, 83, switch 65, and wire 68. Energizing of relay 87 will hook up the coil of said relay with wires 46, 47 direct through closing switch 90 so that said relay will remain energized after switch 88 is broken, and after cam 41 makes one revolution.

After relay 87 is energized as above described, the apparatus is now ready for operation, it being seen that clock 42 is directly in the closed circuit and will continue to operate until plug 6 is pulled out, or until the source of power is disconnected. It is pertinent to note at this point that the energized relay 87 has also closed switch 91, and that one contact of said switch is connected by wire 92 with one contact 93 of push button switch 7, while the other contact 94 of said switch 7 connects with a wire 95 that in turn connects with line 46 through wires 47 to 49 inclusive.

In order to issue a ticket or sheet 3, the contact button 7 is pressed, thereby closing contacts 93, 94. This energizes relay coil 86 through closed switch 91, the other contact of which connects with one terminal of the relay coil 86 through wires 96, 97, while the other terminal of said coil connects with wire 84. The energizing relay 86

by way of closed relay switches 90, 91 of relay 87, upon pressing button 7, causes relay 86 to be connected in the circuit through its own switch 98, one contact of which connects with wire 97 through wire 99, while the other contact connects with wire 48 through wire 100. Thus even though relay 87 is de-energized, the relay 86 will remain energized.

The energizing of relay 86 also closes switch 101, thereby connecting the coil 24 of solenoid 23 in a closed circuit through wire 102 that leads to one end of coil 24. The opposite end of said coil 24 connects with wire 45 through wire 103. The other contact of switch 101 connects with wire 100 that in turn connects with wire 48 and with wire 46 through wire 47.

The time printer is actuated immediately upon energizing coil 24 of solenoid 23, thereby causing switch 65 to open contact 66 and to close contact 61 which breaks the circuit through relays 86, 87 that were connected with contact 66 through wire 83. The solenoid 23 is de-energized allowing its core to drop, thereby actuating rocker arm 74, latch 76, and switch 77 which will start motor 39. The motor 39 causes cam 41 to revolve to close switch 88 thereby re-energizing relay 87 whereupon it will be held energized through its own switch 90 as already described, and in readiness for another operation.

At the beginning of this description the operation of setting the circuit printer 26 for printing upon connecting wires 45, 46 with a source of power through plug 6 has been explained. Any time the circuit through wires 45, 46 is disconnected from the main source of power, a single printing by the circuit printer 26 will occur after the source of power is reconnected.

When door 8 of the cabinet is opened by revolving latch element 10 of lock 9, the said latch element will engage a projection 104 on a pivotally supported member 105 that supports one end of an arm 106 that in turn is pivoted at its opposite end. The pivots supporting member 105 and arm 106 may be secured to any suitable part of the cabinet or part of frame 26. The revolving of latch element 10 against projection 104 will swing the member 105 against a compression spring 107 and from under the end of arm 106, thereby permitting arm 106 to fall. Arm 106 carries an upwardly projecting switch actuating element 108 that swings to close switches 109, 110 upon the dropping of arm 106.

The closing of switch 109 results in energizing the solenoid 31 inasmuch as wire 111 from one contact of said switch connects with one end of the coil 33 of said solenoid while the other contact connects with wire 58 through a wire 112 and which wire 58 in turn connects with wire 45. The other end of coil 33 connects with wire 46 as already described through wires 78, 49, 48, 47.

The energizing of solenoid 31 through closing of switch 109 raises the door printer to position 35 preparatory to printing the symbol 37 upon actuation of the solenoid 23. This elevation of said solenoid core 29 of solenoid 31 also closes switch 116 that is actuated by the raising of extension 27 of said core 29 thereby actuating solenoid 23 to cause a printing by the door and time printer.

Simultaneously with extension 21 of solenoid 23 actuating rocker arm 18, the switch 65 will be actuated to break the switch connection at 66 and to make a connection between wire 68 and wire 69 at 67. Inasmuch as wire 69 connects with the switch 110, and inasmuch as the latter was

closed at the same time as switch 109, an electrical circuit is established through the coil 118 of a solenoid 119. One end of said coil connects with wire 46 by way of wire 120 while the other end of said coil connects with one of the contacts of switch 110 by way of wire 121. The energizing of solenoid 119 causes its core 122 to raise, thereby lifting the arm 106 to a position where it will be supported by member 105 for another operation, which will be caused when door latch 10 is swung back to lock the door 8 as well as when said latch is moved to unlock said door.

The switches 109, 110 will break the circuit through solenoids 23, 31, 119, thereby allowing core 22 of solenoid 23 to fall for actuating the motor 39 for actuating the ticket dispensing mechanism (not shown). The recording device is again ready for a normal operation after the above operations have occurred.

Instead of a latch 10 that is turned by actuation of lock 9, I may provide a latch element 124 (Fig. 3) secured to door 125 for swinging with the door and for actuating. The claims are intended to cover either method or any method or manner whereby an unauthorized unlocking or opening of the cabinet door will actuate means for recording the fact of such opening.

From the description it will be seen that the door printer will print simultaneously with the time printer upon opening and closing the cabinet door, thereby giving the exact time of the opening and of the closing.

Inasmuch as the clock mechanism 12 stops upon disconnecting the source of power, it is obvious that the time printing effected automatically upon reconnecting the source will be the time at which the source was disconnected, and as the circuit printer will print its record simultaneously with the time printer, it will be obvious that the record will show the fact of the disconnection as well as the time thereof. The length of time that the source of power was disconnected is readily seen from comparing the actual time with the time printed by the time printer.

It is to be understood that different circuits and mechanisms may be employed for accomplishing the results herein set forth. The claims are intended to cover such changes as may be made within the scope of the invention. For example, while printing the records on a sheet or strip of paper is preferable, it is obvious that a punch, or the like, may be used for perforating the sheet and thus making the desired record. Also any symbols desired may be employed for making the desired record. Other modifications coming within the scope of the invention may suggest themselves to anyone skilled in the art.

Having described the invention, I claim:

1. In combination with an electrical circuit having a time indicator therein arranged and

adapted to be electrically actuated for recording the time of such actuation on a record sheet, and a source of electricity for said circuit connected therewith, a circuit indicator in said circuit separate from said time indicator actuatable for making a symbol on said sheet, means actuated by connecting said circuit with said source after a disconnection therebetween for simultaneously actuating said time indicator and said circuit indicator for recording the time and said symbol, means in said circuit operative for automatically rendering said circuit indicator inoperative upon a single actuation of said circuit indicator following the operation of connecting said circuit with said source and as long as said source is so connected, and means actuatable by disconnecting said source from said circuit for rendering said circuit indicator operative for actuation thereof upon such reconnection.

2. In time recording apparatus that includes a time printer for printing the time on a record sheet, a cabinet enclosing said time printer and having an opening therein for providing access to the interior of said cabinet, a door for closing said opening, locking means movable to and from a position securing said door closed, said time printer being always positioned for printing the time on such sheet upon actuation thereof, means for so actuating said time printer, a door printer within said cabinet in a normally inoperative position and movable to and from an operative position for actuation by said last mentioned means for printing a symbol on such sheet simultaneously with printing of said time, means actuated by movement of said locking means to a position unlocking said door for so moving said door printer to its said position for printing said symbol, and means actuated by such simultaneous printing by said time printer and said door printer for causing movement of said door printer from said operative position to said inoperative position, said means for actuating said time printer including a platen movable toward and from said time printer, said door printer including a printing type movable to and from a position for printing by actuation of said platen toward said time printer, and a solenoid in an electrical circuit for so moving said platen.

ELBERT V. ABBOTT.
